UNITED STATES PATENT OFFICE

158,191

BRACKET SUPPORT FOR CIGARETTES
OR THE LIKE

Lee A. Hervey, Mountain Lakes, N. J.

Application November 19, 1948, Serial No. 149,725

Term of patent 7 years

(Cl. D85—8)

To all whom it may concern:

Be it known that I, Lee A. Hervey, a citizen of the United States and a resident of Mountain Lakes, in the county of Morris and State of New Jersey, have invented a new, original, and ornamental Design for a Bracket Support for Cigarettes or the like, of which the following is a specification, reference being had to the accompanying drawing, forming part thereof.

Figure 1 is a top plan view of a bracket support for cigarettes or the like showing my new design;

I claim:

The ornamental design for a bracket support for cigarettes or the like, as shown.

LEE A. HERVEY.
